DUST SUCTION DEVICE FOR CLEANING FUR
CLOTHING, ETC.

Stephen Lanyi, Passaic Park, N. J.

Application May 23, 1936, Serial No. 81,349

3 Claims.

(Cl. 15—6)

This invention relates to new and useful improvements in a dust suction device for cleaning furs, clothing and the like.

This application is an improvement over my Patent No. 2,047,787.

An important object of this invention is the construction of the combination brush and vibrator to efficiently perform its work, and the arrangement of mounting this brush and vibrator within the air duct of the device in a particular manner.

A further object of the invention resides in forming the combination brush and vibrator of two distinct end sections separated by a pulley portion, and to drive this device by a belt extending over said pulley portion.

Still further the invention proposes to adjustably mount the ends of the combination brush and vibrator so that it may be set at various tilted positions to obtain a multiplicity of different degrees of operation of the device. A feature of this adjustment resides in the fact that it may be pivoted about the driving pulley as a center so that there need be no changes as far as the driving unit is concerned, for the various adjustments possible.

Still further the invention proposes the provision of a plate formed with a longitudinal slot and adapted to close the top opening in the inverted saucer-like casing, and having edge portions resting upon a flange surrounding said opening. When thus constructed it may be readily removed and replaced when desired, and in addition it may be adapted to hold down the air duct of the device.

A further object of the invention resides in the provision of a flange on the air duct which is adapted to rest beneath the flange from the plate whereby the air duct may be smartly held in position.

Still further the invention contemplates a novel association of the blower with the air duct.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:—

Fig. 1 is a plan view of a device constructed according to this invention.

Fig. 2 is a view similar to Fig. 1 but illustrating the device with the top plate removed.

Fig. 3 is a bottom plan view of the device.

Fig. 4 is a perspective view of a screen member which may be used in conjunction with the device and which is shown in dot and dash lines in Figs. 5 and 6.

Fig. 5 is a transverse sectional view taken on the line 5—5 of Fig. 6.

Fig. 6 is a transverse sectional view taken on the line 6—6 of Fig. 2.

Fig. 7 is a sectional view taken on the line 1—1 of Fig. 6, to which a filter bag has been added.

Fig. 8 is a perspective view of the device.

Fig. 9 is a fragmentary sectional view taken on the line 9—9 of Fig. 5.

Fig. 10 is a bottom view similar to Fig. 3 but showing a modified form of the device.

The dust suction device for furs, clothing and the like, according to this invention, includes an inverted saucer-like casing 10 adapted to be attached upon a table 11 and having a top opening 12. A plate 13 is formed with a longitudinal slot 14 and is adapted to partially close the top opening 12. This plate has an edge portion resting upon a flange portion 12a surrounding the opening 12 and projecting from the casing 10. An air duct 15 is arranged within the casing 10 and extends completely across the slot 14. This air duct is formed with a flange 16 resting upon the flange 12a and disposed beneath the edge portion of the plate 13.

A blower 17 is mounted within the casing 10 and upon one side of the air duct 15. This blower has its suction intake 18 connected with the said duct 15 and has its pressure discharge 19 adapted to be connected with an air filter bag 20 (see Fig. 7). A combination brush and vibrator 21 is arranged within the air duct 15 adjacent and beneath the slot 14 and is adapted to brush and beat furs, clothing and other articles passed over the top of the casing. A means is provided for driving the combination brush and vibrator and includes an electric motor 22. This motor is also utilized to drive the blower 17.

An electric switch 23 is shown mounted upon one side of the saucer-like casing 10 and is for the purpose of controlling the motor 22. This specification does not disclose the wiring of the switch to the motor as it forms no part of the invention.

The plate 13 is held in position by several screws 24 passing through the plate and into the flange 12a. This plate is also formed with several openings 25 in the vicinity of the slot 14 and adapted to receive pegs 26 from a screen 27 adapted to be positioned over the opening 14. This screen is shown in dot and dash lines in Figs. 6 and 5.

The air duct 15 is of a much smaller width than the width of the opening 12 so that when the plate 13 is removed, as shown in Fig. 2, the blower is exposed. A screen element 28 is extended across the suction inlet 18 of the blower. The blower 17 includes a casing 17a in which a blower rotor 17b is mounted. This rotor is

mounted upon the shaft 22^a from the motor 22. The motor is mounted through one side of the casing 10 and is supported upon a shelf 30 included for this purpose. This shelf is attached 5 upon the side wall of the casing 10.

The combination brush and vibrator 21 comprises two distinct sections, the section 21^a and the section 21^b separated by a pulley 21^c. Each of the sections 21^a and 21^b comprises a cylindrical body portion from which two flange blades 21^d radially project. These blades are spaced 120° from each other. Spaced 120° from these blades there is a bristle brush 21^e. The sections 21^a and 21^b are so arranged that the bristle 10 brushes 21^d of the end sections are 180° from each other.

The combination brush and vibrator is mounted upon a shaft 32 which is adjustably supported at its ends. Each of the ends of the shaft 32 20 is rotative in bearing 33 which has a trunnion 34 swivelled in a block 35 vertically adjustable on tracks 36 mounted upon the side walls of the air duct 15. A plurality of set screws 37 are mounted on the tracks for abutting the blocks 25 35 to hold the blocks in adjusted positions.

It is possible to arrange the combination brush and vibrator so that it is level and acts universally throughout the length of the slot 14. If it is desired one of the blocks 35 may be adjusted 30 slightly upwards and the other of the blocks slightly downwards so as not to change the relative distance between the pulley 21 and the motor shaft 22^a, while at the same time changing the operation of the brush and vibrator at the opposite ends of the slot 14. Thus, more violent brushing and vibrating may be accomplished at one end of the slot than the other. It is thus possible to pass coarser materials over the coarser operating side of the brush and vibrator, and finer materials over the other side.

A belt 38 passes over the pulley 21^c and over a pulley 39 mounted on the shaft 22^a. Thus, the motor 22 is capable of operating the combination brush and vibrator.

In Fig. 8 an electric plug 40 is shown associated with a cable 41 which is connected with the motor 22.

In Fig. 10 a slightly modified form of the invention has been disclosed which distinguishes 50 from the prior form merely in the construction of the blower outlet. In this form of the invention the blower outlet 19^a is of elliptical shape, contrasted with the circular shape of the blower outlet 19 (see Fig. 3) in the prior form of the device.

While I have illustrated and described the preferred embodiments of my invention, it is to be understood that I do not limit myself to the precise constructions herein disclosed and the 60 right is reserved to all changes and modifications coming within the scope of the invention as defined in the appended claims.

Having thus described my invention, what I claim as new, and desire to secure by United 65 States Letters Patent is:—

1. In a dust suction device for furs, clothing, etc. including an inverted saucer-like casing adapted to be attached on a table and having a top opening, a plate having a longitudinal slot closing said opening, an air duct within said casing and extending across said slot, a blower mounted within the casing, a combination brush and vibrator within said duct and adjacent said slot for brushing and beating furs, clothing, etc.

passed over the top of said casing, and a means for driving said combination brush and vibrator; means for adjustably mounting the brush and vibrator, comprising a shaft, a pair of spaced hollow cylindrical end sections mounted on said shaft ends, tracks mounted upon the side walls of said air duct, bearing frames at each end of said shaft adapted to vertically adjustably engage said tracks and to support said cylindrical end sections for pivotal movement about a horizontal axis, and a means for holding said bearing frames in their adjusted position to allow said brush and vibrator to be adjusted around a center intermediate the ends of the brush.

2. In a dust suction device for furs, clothing, etc., including an inverted saucer-like casing adapted to be attached on a table and having a top opening, a plate having a longitudinal slot closing said opening, an air duct within said casing and extending across said slot, a blower mounted within the casing, a combination brush and vibrator within said duct and adjacent said slot for brushing and beating furs, clothing, etc., passed over the top of said casing, and a means for driving said combination brush and vibrator; means for adjustably mounting the brush and vibrator, comprising a shaft, a pair of spaced hollow cylindrical end sections mounted on said shaft ends, tracks mounted upon the side walls of said air duct, bearing frames at each end of said shaft adapted to vertically adjustably engage said tracks and to support said cylindrical end sections for pivotal movement about a horizontal axis, and a means for holding said bearing frames in their adjusted position to allow said brush and vibrator to be adjusted around a center intermediate the ends of the brush, said latter-mentioned means comprising set screws threadedly engaging said track and adapted to engage said bearing frames to hold said frames in adjusted position.

3. In a dust suction device for furs, clothing, etc., including an inverted saucer-like casing adapted to be attached on a table and having a top opening, a plate having a longitudinal slot closing said opening, an air duct within said casing and extending across said slot, a blower mounted within the casing, a combination brush and vibrator within said duct and adjacent said slot for brushing and beating furs, clothing, etc., passed over the top of said casing, and a means for driving said combination brush and vibrator; means for adjustably mounting the brush and vibrator, comprising a shaft, a pair of spaced hollow cylindrical end sections mounted on said shaft ends, tracks mounted upon the side walls of said air duct, bearing frames at each end of said shaft adapted to vertically adjustably engage said tracks and to support said cylindrical end sections for pivotal movement about a horizontal axis, and means for holding said bearing frames in their adjusted position to allow said brush and vibrator to be adjusted around a center intermediate the ends of the brush, said latter-mentioned means comprising set screws threadedly engaging said track and being adapted to engage said bearing frames to hold said frames in adjusted position, said shaft end being longitudinally slidably mounted in said bearing frames, so that said bearing frames may be 70 adjusted along a substantially flat plane while said shaft ends move through an arc.

STEPHEN LANYI.
